UNITED STATES PATENT OFFICE

BRUCE A. MAYER, OF SPRINGFIELD, OHIO

INCUBATOR

Application filed June 14, 1926. Serial No. 115,807.

My invention relates to incubators.

It is the object of my invention to provide an incubator without moving parts for the circulation of air and with means for evacuating vitiated air without the necessity of fans or other moving mechanism.

Referring to the drawing:

Figure 1 is a section through the incubator and a section through the circulating and 10 evacuating pipe.

Figure 2 is a section taken on the horizontal plane, as shown by the line 2—2 of Figure 1. Referring to the drawing in detail, 1 is the 15 top of an insulated cabinet of the incubator having side walls 2 and 3 and end walls 4. The incubator is provided with the usual door not shown. The bottom of the cabinet is provided with doors 5 hinged at 6 adjacent a heating compartment 7 beneath the wire 20 screen floor 8. 9 designates generally a heater suitably controlled by a switch 10. 11 designates the bottom of the cabinet just beneath the heater.

The upper part of the cabinet is occupied 25 by a series of egg trays 12 of the usual character supported on guides or slides 13 which are, in turn, supported by the uprights 14.

Circulating pipes for circulating the air are connected at the upper circulating openings 15 and are designated 16, passing down 30 the outside of the cabinet preferably and entering the cabinet at the bottom at 17.

The air is so circulated by reason of the fact that the heated air rises passing into the 35 tube 16, descends as it is cooled and enters again through the opening 17 where it joins the heated air that is rising. Thus, a constant circulation of air is maintained.

In order to draw out vitiated air, I provide 40 an evacuating pipe 18, the lower open end of which 19 is located below the lowermost trays near the bottom of the tray compartment. The pipe passes upwardly and out the cabinet through a sealed opening 20 across the 45 top of the cabinet, as at 21, and extends downwardly in a leg 22 below the top of the cabinet, discharging at 23.

The purpose of the pipe 18 is to remove accumulated carbon dioxide laden air from the 50 lower part of the incubator. The heated car-

bon dioxide laden air rises in the tube 18 and passes out and across the top through pipes 21 and down through pipes 22, out at the discharge end 23. The heated carbon dioxide laden air readily rises through the tube 18 and when it gets into the descending tubes 22 it will fall due to the carbon dioxide laden air being heavier than the surrounding air, and also due to the fact that the surrounding air cools the carbon dioxide that is in the pipes. The descent of the carbon dioxide laden air in pipes 22 is due to the upward pressure of the heated carbon dioxide laden air in the pipe 18, and also due to the downward pressure in pipes 22 owing to the greater weight of the carbon dioxide laden air, carbon dioxide itself being about fifty per cent heavier than air.

I find that it is preferable to extend this leg 22 about eight or ten inches below the top of the casing.

With two pipes 18 of an interior diameter of two inches in a casing six feet high, four feet deep and three feet wide, I can exhaust the entire vitiated air every 8.2 minutes.

By utilizing these pipes, I can draw off through these pipes the carbon dioxide which travels in the lower part of the casing, drawing in fresh air through the bottom of the casing which may be regulated by the trap doors 5.

The temperature within the incubator is approximately 100 degrees Fahrenheit. The temperature of the outside air where the neck of the siphon tube is located is usually from 60 sixty to eighty degrees Fahrenheit.

It will be understood that I desire to comprehend within my invention such modifications as may be necessary to adapt it to varying conditions and uses.

Having thus fully described my invention, what I claim as new and desire to secure by Letters Patent, is:—

In an incubator consisting of a closed casing having air entrance doors at the bottom thereof, a heater in the bottom thereof, a plurality of trays to contain eggs located above said heater, air circulating means consisting of a tube leading from above the trays outside of the incubator back to a point below the

trays, air outlet means consisting of a tube having its open lower end at a point below the trays extending upwardly and out of the incubator across the top of the incubator and discharging at a point below the top of the incubator.

In testimony whereof, I affix my signature.
BRUCE A. MAYER.
